CHARGE FORMING DEVICE

Wilford H. Teeter, Dayton, Ohio, assignor, by
mesne assignments, to Delco Products Corpora-
tion, Dayton, Ohio, a corporation of Dela-
ware

Application October 15, 1928. Serial No. 312,512

24 Claims. (Cl. 261—34)

This invention relates to charge forming de-
vices for internal combustion engines and in par-
ticular to the type of charge forming device which
comprises a plurality of primary carburetors, one
5 for each intake port of the engine, and which
cooperate respectively with a plurality of sec-
ondary mixing chambers located adjacent the
said intake ports. These mixing chambers are
adapted to receive primary fuel mixture from
10 the primary carburetors and under certain op-
erating conditions, to receive additional air sup-
plied through the branches of an air manifold
which supplies air to all of said mixing cham-
bers and is provided with a single air inlet.

15 An example of charge forming devices of this
character is disclosed in the patent of Wilford H.
Teeter and Fred E. Aseltine, No. 1,819,495 granted
August 18, 1931.

In the devices disclosed in the above applica-
20 tions and other devices of this character hereto-
fore designed, various means are provided for
regulating the mixture proportions under vari-
ous operating conditions in order to provide the
mixture necessary to give the most satisfactory
25 engine operation under all conditions of speed
and load. These proportioning devices include
means for enriching the mixture on opening
movements of the throttle to provide a mixture
30 rich enough to give the necessary power dur-
ing the acceleration period. Various forms of
fuel pumps have heretofore been provided to
supply additional fuel to enrich the mixture as
described. These pumps have not been alto-
35 gether satisfactory. For instance, it has been
found necessary to provide check valves in the
delivery conduits of such pumps in order to pre-
vent the liquid in said conduits running back
40 to the source of supply when the pump is not
in operation. These check valves were unseated
to some extent by the vibration of the engine
and fail to produce the desired result, hence the
pumps are not uniform in their action and a
45 delay occurs nearly always before the pumped
fuel reached the mixture passage after the open-
ing of the throttle, the amount of delay being
variable and determined by the degree of engine
vibration and the time interval between opera-
50 tions of the pump. Also mechanically operated
pumps add to the manufacturing costs and re-
quire the provision of parts liable to get out
of proper adjustment, or subject to wear, and
are not always effective to supply the desired
55 amount of accelerating fuel, since the quantity of

fuel is dependent on the throttle movement in-
stead of the change in engine suction.

One of the objects of the present invention
is to provide means for enriching the mixture
on opening movements of the throttle, which is
effective to supply the desired amount of fuel
under all operating conditions, is uniform in its
action, and simple in construction. It is an-
other object of this invention to provide means
for enriching the mixture during the acceleration
period, which is effective to enrich the mixture
on any opening movement of the throttle and
substantially simultaneously with such move-
ment. It is a more specific object of the in-
vention to provide means for enriching the mix-
ture during the accelerating period which is
always effective to enrich the mixture an amount
proportional to the increase in engine suction
on any opening movement of the throttle and
is controlled in its action by said throttle.

According to the present invention, these ob-
jects are accomplished by the provision of an
auxiliary fuel reservoir for supplying additional
fuel during the accelerating period and into
which a fuel delivery tube extends which dur-
ing normal operation does not reach the fuel in
said reservoir, rendering the said reservoir in-
effective during normal running. This auxiliary
reservoir is integral with the cylinder of the air
valve dash pot which is lifted as the throttle is
opened, simultaneously increasing the resistance
to opening of the air valve and immersing the
fuel delivery tube to render the means for sup-
plying additional fuel effective. According to this
invention the fuel delivery tube communicates
with the primary mixture passages so that ad-
ditional fuel will be discharged into the primary
mixture which is passing therethrough at high
velocity and is, therefore, supplied at the intake
ports almost simultaneously with the opening of
the primary throttle.

Further objects and advantages of the present
invention will be apparent from the following de-
scription, reference being had to the accompan-
ying drawing wherein a preferred embodiment of
one form of the present invention is clearly
shown.

In the drawing:

Fig. 1 is a vertical longitudinal section through
a charge forming device in which the present in-
vention is incorporated.

Fig. 2 is an end elevation of the main car-
buretor unit forming part of said charge forming
device.

Figs. 3 and 4 are detail sections on the lines 3—3 and 4—4 of Fig. 1.

Fig. 5 is a fragmentary detail view showing the construction of the dashpot by-pass.

5 The device disclosed comprises a main air manifold 10 having three outlet branches, the middle branch 12 being shown herein. Each of these branches communicates with one of the intake ports 14 of a multicylinder engine and are 10 each provided with an attaching flange 16 for securing the manifold to the block in the usual manner. Adjacent the inlet of the manifold is provided a flange 18 to which the main carburetor unit is adapted to be attached, as shown in Fig. 1.

15 The carburetor unit comprises a main housing 20 having an attaching flange 22 adapted to be secured to the flange 18 by screws 24. An air inlet horn 26 is secured in position to register with an opening in the upper wall of the housing 20, 20 in any suitable way. A casting 28 supporting the cylinder of a dash pot, hereinafter more fully described, is secured to the bottom of the housing 20 and a sheet metal fuel bowl is held tight against a shoulder 30 formed on the casting 28.

25 Fuel is conducted to the bowl from a main source of supply through a conduit, not shown herein, and the flow of fuel is controlled by a float 34 operating in the usual manner to maintain a substantially constant fuel level in the bowl.

30 Fuel flows from the bowl to a plurality of fuel nozzles 36, one of which is located in each of the primary mixture passages 38, the construction of which is briefly described hereinafter.

35 The fuel conduit between the fuel bowl and the nozzles comprises a vertical fuel conduit connecting at its upper end with a horizontal fuel canal 42 formed in a block 43 secured to the bottom wall of the main housing 20 and supporting the conduit 40. The canal 42 communicates with the nozzles 36 through orifices 44 and fuel is admitted to the passage 40 at low speeds through a fixed metering orifice 46 only, while at higher speeds additional fuel is admitted through an orifice 48 controlled by a valve 50 in the manner fully set forth in the above mentioned copending application Serial No. 221,371.

45 Fuel is lifted from the fuel bowl through the above described passages and nozzles 36 to the mixture passages 38 by the suction therein.

50 Closing movements of the throttle cause a reduction in the suction in the mixture passages which might permit the fuel column to drop sufficiently to cause a temporary fuel starving of the engine unless means were provided to prevent it. Such means comprises a check valve 52 received in an enlarged chamber 54 at the junction of channels 40 and 42. On reduction of suction in the mixture passages, this valve seats on a rib 56 projecting upwardly from the bottom of chamber 54 preventing downward flow of fuel from said chamber. A two stage metering valve 57 regulates the flow of fuel through conduit 40 in the manner set forth in the copending application, Serial No. 221,371.

55 Each primary fuel nozzle is provided with a main fuel outlet 58 in the top of the nozzle and a secondary fuel outlet comprising two orifices 60 and 62 in the vertical wall of the nozzle near the bottom of the mixture passage. At relatively high speeds the suction at the nozzles is enough to lift fuel from the main fuel outlet as well as from holes 60 and 62, but at idling or low speed operation under load, the suction is sufficient to lift fuel only to some point between the tops of the nozzles and orifices 60 and 62, fuel flow-

ing from such orifices by action of gravity. The primary mixture passages 38 are parallel to each other and close together, as indicated in Fig. 3 and when the carburetor is attached to the manifold, these passages register with conduits which convey the primary mixture to the secondary mixing chambers, as fully disclosed in the copending application, Serial No. 221,371. One of these conduits in the form of a tube 68, fixed in the wall of the branch 12 of the manifold and conveying primary mixture to the secondary mixing chamber formed in that branch, is shown in Fig. 1.

60 A single throttle valve 64 extends across all of the primary mixture passages to control the flow therethrough and is provided with grooves 66 which register with the mixture passages. This throttle is journalled in the housing 20 and is operated by means not shown herein and forming no part of the present invention, but fully disclosed in the above application, Serial No. 221,371.

65 Substantially all the air entering the carburetor flows through the air horn 26, controlled by a main air valve 70, normally held against a seat 72 by a spring 74 received between the valve and a flange 76 projecting from a sleeve 78 slidably mounted on a stationary sleeve 80, fixed in the housing 20 and serving as a guide sleeve for the stem 82 to which the air valve is secured.

70 When it is desired to choke the carburetor to facilitate starting the engine, the flange is adapted to be lifted, by means not shown herein, until the upper end of the sleeve 78 engages the valve 70 to hold it against its seat. Sufficient air to 100 carry the starting fuel from the nozzles to the engine intake ports is admitted through orifices 84 formed in the housing 20, as shown in Fig. 1.

75 The valve 70 admits air to a main air chamber 88 from which air flows to the primary mixture passages through an orifice 90 in the floor of the air chamber and to the secondary mixing chambers through a passage 92 which communicates with the inlet of the manifold 10. A manually operable throttle 94 controls the flow of 110 air through passage 92 and the operating connections for the valve are fully shown and described in the above application, Serial No. 221,371.

80 To prevent fluttering of the air valve and to 125 retard its opening movement for the purpose of forming the desired mixture for acceleration, a dash pot is provided, including a cylinder 100 located within the fuel bowl and cooperating with a piston 102, slidable on a sleeve 104, pinned to 130 the lower end of the valve stem 82. The sleeve is provided with a flange 106 having an annular bead 108 serving as a valve seat for the piston which acts as a valve, said piston being normally held against the bead by a spring 110 received between the piston and a nut 112 screwed on the sleeve. The piston is provided with ports 114 and under certain operating conditions, the piston is lifted off the bead 108 permitting fuel to pass through the ports 114 from below the 140 piston and relieving the dash pot as described in the above mentioned application. The flange is provided with ports 116, controlled by a check valve 118 to permit free closing movement of the air valve.

85 A cylinder 100 is vertically slidable within a guide 120 integral with the casting 28 and is adapted to be lifted on opening movements of the throttle by means presently described. Apertures 122 and 124 in the guide and cylinder re- 150

spectively admit fuel to the said cylinder from the main fuel bowl. The cylinder is also provided with a by-pass pipe, such as fully shown in Patent No. 1,819,495, the lower end 126 of which is shown in dotted lines in Fig. 1.

To lift the cylinder by means of the throttle, said cylinder is provided adjacent its upper end with a groove 130 which receives lugs 132 carried by the arms of a bifurcated lever 134 secured on a rock shaft 136. This shaft has fixed thereon, outside the housing 20, an arm 138 and projecting therefrom is a lug 140 through which a rod 142 is slidable. One end of the rod is threaded into a lug 144 projecting from a lever 146 loosely mounted on the rock shaft 136. Adjustable nuts 148 are threaded on the other end of the rod and a spring 150 is received between said nuts and the lug 140. The spring, therefore, urges the lug 140 against a stop member 152 carried by the rod, and by loosening a lock nut 154, normally locking the rod fixed in the lug 144, and turning the rod, the angular relation of the arm 138 and lever 146 may be adjusted and by adjusting the nuts 148 the tension of the spring 150 may be varied. The lever 146 is provided with an arcuate slot 156 which receives a block 158 provided with means (not shown) by which it may be clamped in any desired position in said slot. The block provides a bearing for a pin 160 attached to a link 162 pivotally connected at its upper end to a lever 164 pivotally mounted at 166. A cam 168, secured to a spindle 169 projecting from one end of the primary throttle 64 engages the lever 164, and when the spindle is turned in a clockwise direction, as viewed in Fig. 2, the lever 164 is rotated in a counter-clockwise direction. This movement of lever 164 will move the lever 146 counter-clockwise on the rock shaft 136 and through the medium of the spring 150 will move the arm 138 in the same direction rocking the shaft 136 so as to move the bifurcated lever 134 clockwise in Fig. 1, lifting the dash pot cylinder and increasing the resistance to opening of the air valve whenever the throttle is opened, so as to enrich the mixture for acceleration.

The provision of the resilient lifting means for lifting the dash pot cylinder enables the lifting movement to take place throughout a greater period of time than if a positive lifting device were employed. This will cause the opening movement of the air valve to be retarded for a longer time, thus providing the richer mixture desirable for acceleration over a longer period.

The above described device is incapable of sufficiently enriching the mixture to secure entirely satisfactory engine operation during the accelerating period and according to the present invention additional means are provided for enriching the mixture during acceleration, such means comprising an additional fuel jet in each primary mixture passage which is normally inoperative, but which is rendered operative on opening movements of the throttle. Positioned immediately in advance of the main fuel jet in each mixture passage is an auxiliary fuel jet 170. These jets communicate through orifices 172 with a fuel canal 174 in the block 143. A bore 176 in the block connects the canal 174 with a vertical passage in a tube 178 depending from the block 143 and attached to the lower face thereof. The dash pot cylinder has formed integral therewith a smaller auxiliary cylinder 180 communicating with the dash pot cylinder by means of a passage 182 and adapted to have fuel

standing therein at the same level as in the dash pot cylinder at all times that the dash pot piston is stationary. The fuel supply tube 178 projects into the upper open end of the auxiliary cylinder to a point above the normal level of fuel therein and is spaced from the wall of said cylinder to admit passage of air around the tube.

When the various operating parts are stationary, the fuel supply tube is ineffective to supply fuel to the auxiliary jets, but whenever the throttle is opened to increase the speed the dash pot cylinder 100 is lifted, lifting the auxiliary cylinder to a position where the lower end of the tube 178 is immersed in the fuel in said auxiliary cylinder so that the auxiliary jets become effective to supply additional fuel.

The piston in the dash pot is moved downwardly when the air valve opens following any opening movement of the throttle, and throughout the downward motion of such piston the level of fuel in the auxiliary cylinder is maintained above the end of tube 178, because fuel is forced from the dash pot cylinder into said auxiliary cylinder as long as the dash pot piston moves, although the dash pot cylinder may be at rest before the motion of the piston ceases.

The flow of fuel therefrom is determined entirely by the suction in the mixture passages and takes place immediately on opening movement of the throttle, beginning substantially simultaneously with said opening movement and continuing as long as the lower end of the tube 178 remains immersed in the fuel. Since there is no pumping of fuel into the mixture passages and the flow of fuel from the auxiliary jets is effected solely by the suction, the flow therefrom is always proportional to the increase in suction and on a given opening movement of the throttle under the same operating conditions, the flow from the auxiliary jets will always be the same. Since the device for supplying additional fuel has no operating parts subject to wear and is very simple in its construction, it is cheap to manufacture and does not get out of order, nor need repairs. Moreover, it is provided with no check valves in the delivery conduit to give rise to the difficulties heretofore mentioned and is always effective substantially simultaneously with the opening of the throttle.

The flow of fuel continues as long as the level of fuel in the auxiliary cylinder is above the lower end of the tube, and when the throttle is stationary and the end of said tube uncovered, air flows therethrough, but in such small quantities that it does not interfere with proper mixture proportioning even at low speeds.

While the form of embodiment of the present invention as herein disclosed, constitutes a preferred form, it is to be understood that other forms might be adopted, all coming within the scope of the claims which follow.

What is claimed is as follows:

1. A charge forming device for internal combustion engines comprising a mixture passage, means for supplying fuel and air thereto, a throttle, a fuel reservoir, a fuel supply tube adapted to supply additional fuel to said mixture passage on opening of the throttle and normally terminating above the fuel level in said reservoir, an air valve controlling the admission of air to the mixture passage and means operated by said throttle and said air valve for raising the fuel level adjacent said tube.

2. A charge forming device for internal com-

- bustion engines comprising a mixture passage, means for supplying fuel and air thereto, a throttle, a fuel reservoir, a fuel supply tube adapted to supply additional fuel to said mixture passage 5 on opening of the throttle and normally terminating above the fuel level in said reservoir, an auxiliary reservoir adapted to supply fuel to said supply tube and means operated by the throttle for raising said auxiliary reservoir to bring the 10 fuel level above the end of said supply tube.
3. A charge forming device for internal combustion engines comprising a mixture passage, means for supplying fuel and air thereto, a throttle, a fuel reservoir, a fuel supply tube adapted to 15 supply additional fuel to said mixture passage on opening of the throttle and normally terminating above the fuel level in said reservoir, an auxiliary reservoir adapted to supply fuel to said supply tube, means operated by the throttle for raising said reservoir to lift the fuel above the 20 end of said supply tube, an air valve and means operated by said valve for lifting the fuel in said reservoir above the end of said supply tube.
4. A charge forming device for internal combustion engines comprising a mixture passage, means for supplying fuel and air thereto, a throttle, means for supplying a quantity of additional fuel to the mixture passage on opening movements of the throttle proportional to the increase 25 in suction in the mixture passage, an air valve controlling admission of air to the mixture passage and means operated by the throttle for rendering said fuel supply means effective and simultaneously increasing the resistance to opening 30 of the air valve.
5. A charge forming device for internal combustion engines comprising a mixture passage, means for supplying fuel and air thereto, a throttle, an air valve for controlling the admission 35 of air to the mixture passage, a dash pot controlling operation of said air valve comprising a movable cylinder and piston, means for supplying a quantity of additional fuel to the mixture passage on opening movements of the 40 throttle proportional to the increase in suction in the mixture passage, and means operated by the throttle for simultaneously moving the dash pot cylinder to increase the resistance to opening 45 of the air valve and for rendering said fuel supply means effective.
6. A charge forming device for internal combustion engines comprising a mixture passage, means for supplying fuel and air thereto, a throttle, an air valve for controlling the admission 50 of air to the mixture passage, a dash pot controlling operation of said air valve comprising a movable cylinder and piston, a fuel supply tube for supplying additional fuel to the mixture passage to enrich the mixture for acceleration, 55 an auxiliary fuel reservoir movable with said cylinder and adapted to supply fuel to said fuel supply tube but being normally ineffective and means operated on opening movements of the 60 throttle to move the dashpot cylinder to render said fuel supply tube effective.
7. A charge forming device for internal combustion engines comprising a secondary mixing chamber, means for supplying air to said secondary mixing chamber, a primary mixture passage 65 delivering a primary fuel mixture to said secondary mixing chamber, a primary throttle for regulating the effective area of the primary mixture passage, means for supplying fuel and air to said primary mixture passage, and another fuel supply means for temporarily supplying ad- 70 ditional fuel to the primary mixture passage on opening movements of the primary throttle to enrich the mixture during the acceleration period.
8. A charge forming device for internal combustion engines comprising a secondary mixing chamber, means for supplying air to said secondary mixing chamber, a primary mixture passage delivering a primary fuel mixture to said secondary mixing chamber, a primary throttle for regulating the effective area of the primary mixture passage, means for supplying fuel and air to said primary mixture passage, a normally ineffective fuel supply means for temporarily supplying additional fuel to the primary mixture passage during the acceleration period, and means operated by the primary throttle for rendering said fuel supply means effective. 80
9. A charge forming device for internal combustion engines comprising a secondary mixing chamber, means for supplying air to said secondary mixing chamber, a primary mixture passage delivering a primary fuel mixture to said secondary mixing chamber, a primary throttle for regulating the effective area of the primary mixture passage, means for supplying fuel and air to said primary mixture passage, a normally ineffective fuel supply means for temporarily supplying additional fuel to the primary mixture passage during the acceleration period, and means operated by the primary throttle for rendering said fuel supply means effective. 85
10. A charge forming device for internal combustion engines comprising a secondary mixing chamber, means for supplying air to said secondary mixing chamber, a primary mixture passage delivering a primary fuel mixture to said secondary mixing chamber, a primary throttle for regulating the effective area of the primary mixture passage, means for supplying fuel and air to said primary mixture passage, a normally ineffective fuel supply means for temporarily supplying additional fuel to the primary mixture passage during the acceleration period, and means operated by the primary throttle for rendering said fuel supply means effective. 90
11. A charge forming device for internal combustion engines comprising a secondary mixing chamber, a primary mixture passage delivering a primary fuel mixture to said secondary mixing chamber, a primary throttle for regulating the effective area of the primary mixture passage, means for supplying fuel and air to said primary mixture passage, a main air valve controlling the admission of air to the mixture passage, another fuel supply means for temporarily supplying additional fuel to the primary mixture passage to enrich the mixture during the acceleration period, and means operated by the air valve for rendering said fuel supply means effective, as said primary throttle is opened. 105
12. A charge forming device for internal combustion engines having, in combination, a plurality of primary carburetors adapted to supply a primary fuel mixture to a plurality of secondary mixing chambers, means for admitting fuel and air to the primary carburetors, and a single means for supplying additional fuel to all of said primary carburetors during the acceleration period. 110
13. A charge forming device for internal combustion engines having, in combination, a plurality of primary carburetors adapted to supply a primary fuel mixture to a plurality of secondary mixing chambers, means for admitting fuel and air to the primary carburetors, a single air valve 115
14. A charge forming device for internal combustion engines having, in combination, a plurality of primary carburetors adapted to supply a primary fuel mixture to a plurality of secondary mixing chambers, means for admitting fuel and air to the primary carburetors, a single air valve 120
15. A charge forming device for internal combustion engines having, in combination, a plurality of primary carburetors adapted to supply a primary fuel mixture to a plurality of secondary mixing chambers, means for admitting fuel and air to the primary carburetors, a single air valve 125
16. A charge forming device for internal combustion engines having, in combination, a plurality of primary carburetors adapted to supply a primary fuel mixture to a plurality of secondary mixing chambers, means for admitting fuel and air to the primary carburetors, a single air valve 130
17. A charge forming device for internal combustion engines having, in combination, a plurality of primary carburetors adapted to supply a primary fuel mixture to a plurality of secondary mixing chambers, means for admitting fuel and air to the primary carburetors, a single air valve 135
18. A charge forming device for internal combustion engines having, in combination, a plurality of primary carburetors adapted to supply a primary fuel mixture to a plurality of secondary mixing chambers, means for admitting fuel and air to the primary carburetors, a single air valve 140
19. A charge forming device for internal combustion engines having, in combination, a plurality of primary carburetors adapted to supply a primary fuel mixture to a plurality of secondary mixing chambers, means for admitting fuel and air to the primary carburetors, a single air valve 145
20. A charge forming device for internal combustion engines having, in combination, a plurality of primary carburetors adapted to supply a primary fuel mixture to a plurality of secondary mixing chambers, means for admitting fuel and air to the primary carburetors, a single air valve 150

- controlling the admission of air to said primary carburetors, a dashpot controlling movement of said valve, means for supplying additional fuel to the primary carburetors during the acceleration period, and means associated with said dashpot for controlling the effectiveness of said fuel supply means. 80
14. A charge forming device for internal combustion engines comprising a secondary mixing chamber, means for supplying air to said secondary mixing chamber, a primary mixture passage delivering a primary mixture of fuel and air to said secondary mixing chamber, means for supplying fuel and air to said primary mixture passage, a primary throttle controlling the flow through the primary mixture passage, and means for temporarily supplying additional fuel to the primary mixture passage anterior to the throttle during the acceleration period. 85
15. A charge forming device for internal combustion engines comprising a secondary mixing chamber, a primary mixture passage delivering a primary mixture of fuel and air to said secondary mixing chamber, means for supplying fuel and air to said primary mixture passage, a primary throttle controlling the flow through the primary mixture passage, a secondary air passage supplying air to the secondary mixing chamber, a secondary throttle controlling the flow of air therethrough, means for supplying additional fuel to the primary mixture passage during the acceleration period and means operated by the primary throttle for rendering said fuel supply means effective. 90
16. A charge forming device for internal combustion engines comprising a secondary mixing chamber, a primary mixture passage delivering a primary mixture of fuel and air to said secondary mixing chamber, means for supplying fuel and air to said primary mixture passage, a primary throttle controlling the flow through the primary mixture passage, a secondary air passage supplying air to the secondary mixing chamber, a secondary throttle controlling the flow of air therethrough, means for supplying additional fuel to the primary mixture passage during the acceleration period and means operated by the primary throttle for rendering said fuel supply means effective. 95
17. A charge forming device for internal combustion engines comprising a secondary mixing chamber, a primary mixture passage delivering a primary mixture of fuel and air to said secondary mixing chamber, means for supplying fuel and air to said primary mixture passage, a primary throttle controlling the flow through the primary mixture passage, a secondary air passage supplying air to the secondary mixing chamber, a secondary throttle controlling the flow of air therethrough and adapted to be opened after the primary throttle has made a predetermined opening movement, means for supplying additional fuel to the primary mixture passage during the acceleration period, and means operated by the primary throttle both before and after the opening of the secondary throttle for rendering said fuel supply means effective, whereby the mixture is enriched during acceleration at any speed. 100
18. A charge forming device for internal combustion engines comprising a secondary mixing chamber, located adjacent the engine intake port, means for supplying air to said secondary mixing chamber, a primary mixture conduit adapted to deliver a primary fuel mixture to said secondary mixing chamber, a primary throttle in said mixture passage for controlling the flow therethrough, means for supplying fuel and air to said primary mixture passage, and another fuel supply means for temporarily supplying additional fuel to the primary mixture passage on opening movements of the primary throttle, to enrich the mixture during the acceleration period. 105
19. A charge forming device for internal combustion engines comprising a secondary mixing chamber, a primary mixture passage adapted to supply a primary fuel mixture to the secondary mixing chamber, a secondary air passage for supplying air to said secondary mixing chamber, means for supplying air and fuel to said primary mixture passage, said primary mixture passage and said primary air passage being of substantially the same length and another fuel supply means for temporarily supplying additional fuel to the primary mixture passage on opening movements of the primary throttle, to enrich the mixture during the acceleration period. 110
20. A charge forming device for internal combustion engines comprising a secondary mixing chamber, a primary mixture passage adapted to supply a primary fuel mixture to the secondary mixing chamber, a secondary air passage for supplying air to said secondary mixing chamber, a fuel inlet for supplying fuel to the primary mixture passage, a single air inlet admitting air to both said secondary air passage and said primary mixture passage, and another fuel supply means for temporarily supplying additional fuel to the primary mixture passage on opening movements of the primary throttle to enrich the mixture during the acceleration period. 115
21. A charge forming device for internal combustion engines having in combination a plurality of secondary mixing chambers, a plurality of primary mixture passages for supplying a primary mixture of fuel and air to said secondary mixing chambers, one of said primary mixture passages being associated with each of said secondary mixing chambers, means for supplying fuel and air to all of said primary mixture passages, a single secondary air passage for supplying air to all of said secondary mixing chambers and a single fuel supply means for supplying additional fuel to all of said primary mixture passages. 120
22. A charge forming device for internal combustion engines having in combination a plurality of secondary mixing chambers, a plurality of primary mixture passages for supplying a primary mixture of fuel and air to said secondary mixing chambers, one of said primary mixture passages being associated with each of said secondary mixing chambers, means for supplying fuel and air to all of said primary mixture passages, a single secondary air passage for supplying air to all of said secondary mixing chambers, and a single fuel supply means for supplying additional fuel to all of said primary mixture passages, said means comprising a fuel supply conduit having a single inlet and a branched outlet comprising a plurality of branches each of which supplies fuel to one of said primary mixture passages. 125
23. A charge forming device for internal combustion engines comprising a mixture passage, means for supplying fuel and air thereto during normal operation, a throttle, another normally inoperative fuel supply means adapted to supply additional fuel to the mixture passage during the acceleration period, said means being constructed to supply during each acceleration period a total quantity of fuel which is proportional to the increase in suction in the mixture passage. 130
24. A charge forming device for internal combustion engines comprising a secondary mixing chamber, a primary mixture passage adapted to supply a primary fuel mixture to said secondary mixing chamber, means for supplying air to said secondary mixing chamber, means for supplying air and fuel to said primary mixture passage at

- adjacent the point where said additional fuel is delivered, and means operated by the throttle for causing said normally inoperative fuel supply means to become operative.
- 5 24. A charge forming device for internal combustion engines comprising a mixture passage, fuel and air inlets for supplying fuel and air thereto during normal operation, a throttle, means for supplying additional fuel to the mixture passage during the acceleration period, said means including a separate fuel jet for delivering fuel to the mixture passage and being constructed to supply during each acceleration period a total quantity of fuel which is proportional to the increase of suction in said mixture passage adjacent said jet during the acceleration period, and means operated by the throttle on opening movements thereof for rendering said additional fuel supply means operative. 80
- 10 15. A mixture passage for internal combustion engines, having a fuel inlet, an air inlet, a mixture outlet, a fuel jet, and a fuel valve, the fuel valve being located in the mixture passage adjacent the point where said additional fuel is delivered, and means operated by the throttle for causing said normally inoperative fuel supply means to become operative. 90
- 20 25. A mixture passage for internal combustion engines, having a fuel inlet, an air inlet, a mixture outlet, a fuel jet, and a fuel valve, the fuel valve being located in the mixture passage adjacent the point where said additional fuel is delivered, and means operated by the throttle for causing said normally inoperative fuel supply means to become operative. 95
- 30 35. A mixture passage for internal combustion engines, having a fuel inlet, an air inlet, a mixture outlet, a fuel jet, and a fuel valve, the fuel valve being located in the mixture passage adjacent the point where said additional fuel is delivered, and means operated by the throttle for causing said normally inoperative fuel supply means to become operative. 100
- 35 40. A mixture passage for internal combustion engines, having a fuel inlet, an air inlet, a mixture outlet, a fuel jet, and a fuel valve, the fuel valve being located in the mixture passage adjacent the point where said additional fuel is delivered, and means operated by the throttle for causing said normally inoperative fuel supply means to become operative. 105
- 40 45. A mixture passage for internal combustion engines, having a fuel inlet, an air inlet, a mixture outlet, a fuel jet, and a fuel valve, the fuel valve being located in the mixture passage adjacent the point where said additional fuel is delivered, and means operated by the throttle for causing said normally inoperative fuel supply means to become operative. 110
- 50 55. A mixture passage for internal combustion engines, having a fuel inlet, an air inlet, a mixture outlet, a fuel jet, and a fuel valve, the fuel valve being located in the mixture passage adjacent the point where said additional fuel is delivered, and means operated by the throttle for causing said normally inoperative fuel supply means to become operative. 115
- 60 65. A mixture passage for internal combustion engines, having a fuel inlet, an air inlet, a mixture outlet, a fuel jet, and a fuel valve, the fuel valve being located in the mixture passage adjacent the point where said additional fuel is delivered, and means operated by the throttle for causing said normally inoperative fuel supply means to become operative. 120
- 70 75. A mixture passage for internal combustion engines, having a fuel inlet, an air inlet, a mixture outlet, a fuel jet, and a fuel valve, the fuel valve being located in the mixture passage adjacent the point where said additional fuel is delivered, and means operated by the throttle for causing said normally inoperative fuel supply means to become operative. 125
- 80 85. A mixture passage for internal combustion engines, having a fuel inlet, an air inlet, a mixture outlet, a fuel jet, and a fuel valve, the fuel valve being located in the mixture passage adjacent the point where said additional fuel is delivered, and means operated by the throttle for causing said normally inoperative fuel supply means to become operative. 130
- 90 95. A mixture passage for internal combustion engines, having a fuel inlet, an air inlet, a mixture outlet, a fuel jet, and a fuel valve, the fuel valve being located in the mixture passage adjacent the point where said additional fuel is delivered, and means operated by the throttle for causing said normally inoperative fuel supply means to become operative. 135
- 100 105. A mixture passage for internal combustion engines, having a fuel inlet, an air inlet, a mixture outlet, a fuel jet, and a fuel valve, the fuel valve being located in the mixture passage adjacent the point where said additional fuel is delivered, and means operated by the throttle for causing said normally inoperative fuel supply means to become operative. 140
- 110 115. A mixture passage for internal combustion engines, having a fuel inlet, an air inlet, a mixture outlet, a fuel jet, and a fuel valve, the fuel valve being located in the mixture passage adjacent the point where said additional fuel is delivered, and means operated by the throttle for causing said normally inoperative fuel supply means to become operative. 145
- 120 125. A mixture passage for internal combustion engines, having a fuel inlet, an air inlet, a mixture outlet, a fuel jet, and a fuel valve, the fuel valve being located in the mixture passage adjacent the point where said additional fuel is delivered, and means operated by the throttle for causing said normally inoperative fuel supply means to become operative. 150
